UNITED STATES PATENT OFFICE

NELLIE OLIVE HENAUT, OF BUTTE, MONTANA

MILLINER'S SHEARS

Application filed March 6, 1929. Serial No. 344,903.

The invention relates to improvements in milliner's shears of the general type shown in my U. S. Patents Nos. 617,018; 1,432,246 and 1,511,964. It is the principal object of the present invention to provide an improved construction which embodies unique means for tightening a bent wire connection of a hat frame, for instance, at the point where a substantially radial brim wire is joined to a peripheral brim wire by bending the former around the latter. When hat frames are received for covering by milliners, such bent wire connections are very often loose but the present invention provides effective means whereby they may be tightened.

Another object of the invention is to provide a novel construction whereby a lug is provided on one blade of the shears behind the blade pivot, said lug having the two-fold function of spreading the portions of the blades behind said pivot to hold their cutting edges in effective cutting engagement with each other, and adding area to one of the co-operable jaws which are employed for tightening the wire connections of hat frames.

With the foregoing in view, the invention resides in the novel subject matter hereinafter described and claimed, description being accomplished by reference to the accompanying drawings.

Fig. 1 is a perspective view of the improved shears.

Fig. 2 is a view similar to Fig. 1 but showing the shears in use for tightening a bent wire connection of a hat frame.

Fig. 3 is an enlarged fragmentary side elevation.

Figs. 4 and 5 are perspective views of the two blades and associated features of construction.

In the drawings above briefly described, the numerals 6 and 7 denote two blades pivoted together at 8 and provided with rearwardly projecting shanks 9 carrying the usual or any preferred handles 10. The shears possess a number of features of construction common to one or more of the patents above mentioned, but as the present improvements are related only to certain of these old fea-

tures, description of the others will be omitted.

A slight distance behind the pivot 8, the blades 6—7 are provided with laterally projecting wire-cutting lugs 12—13 respectively, whose construction and arrangement are substantially the same as shown in Patent 1,511,964. In front of the lug 12 and integral with the inner edge of the blade 6, is a flange 14 which projects laterally across or in the path of the inner edge of the other blade 7, the rear end of said flange 14 being integral with the substantial body of metal forming said lug 12, so that the latter effectively reinforces said flange. Between its ends, this flange is provided with a notch 15 for a purpose to appear.

The outer side of the blade 7 is provided immediately behind the pivot 8, with a boss 16 which is integral with said blade and disposed at the inner edge of the latter, said boss and the flange 14 being co-operable in providing jaws between which a bent wire connection 17 of a hat frame may be compressed and thus tightened. When this operation is being performed, one of the wires 18 of the hat frame may well extend longitudinally of the lug 12 and flange 14 but somewhat oblique thereto, and another of the wires 19 is then received in the notch 15. With the hat frame thus relatively positioned with regard to the shears as shown in Fig. 2, movement of the two handles 10—10 toward each other will effectively compress and tighten the connection 17 between the jaws 14—16.

Integral with the inner side of the blade 7, extending to the inner edge of the latter and disposed directly opposite the boss 16, is a slight lateral enlargement 20 which adds to the effective area of the boss-formed jaw 16. This enlargement 20 also contacts with the inner side of the blade 6 behind the pivot 8 and hence serves as a spreader for the portions of the blades behind the pivot, thereby urging the front portions of these blades laterally toward each other to insure effective cutting engagement of their edges. I am aware that there is no patentable novelty merely in providing a projection or lug on one blade of a pair of shears to act against the other blade

and insure proper cutting engagement of their edges with each other. However, particular attention is invited to the exact location of the projection 20 which I have provided, thereby giving said projection a two-fold function as explained. Positioning of the projection 20 so that it would only act to urge the blades laterally toward each other would not fall within the scope of my invention but positioning this projection so that it also adds to the effective area of the boss-formed jaw 16, I consider an important and patentable advance. Preferably, the active side of this jaw 16 is formed with a shallow concave recess 21 to receive a portion of the connection 17 as shown in Fig. 2.

It will be seen from the foregoing that I have so added to the construction which is old in my prior patents as to produce a new and advantageous article possessing advantages not hitherto obtainable, and it is not only the co-operative relation between the new features of construction, but their relation with the cutting lugs 12-13, which I seek to protect by this application.

I claim:

1. In milliner's shears, crossed pivoted blades and handle-carrying shanks projecting rearwardly beyond the blade pivot; a flange behind the blade pivot integral with the inner edge of one blade and projecting laterally across the inner edge of the other blade, and a boss integral with the outer side of said other blade at the inner edge of the latter, said boss and flange being disposed in co-operative relation with each other to provide jaws for tightening a bent wire connection of a hat frame.

2. A structure as specified in claim 1; the side of said boss toward said flange having a concave recess to receive the bent wire connection.

3. A structure as specified in claim 1; the outer edge of said flange being formed with a notch to receive one of the hat frame wires leading to said connection.

4. A structure as specified in claim 1; the side of said boss toward said flange having a concave recess to receive the bent wire connection, the outer edge of said flange being formed with a notch to receive one of the hat frame wires leading to said connection.

5. In milliner's shears, crossed blades, handle-carrying shanks projecting rearwardly from said blades and co-operative lateral wire-cutting lugs on said blades spaced behind the blade pivot; a flange behind said pivot integral with the inner edge of one of said blades and projecting laterally across the inner edge of the other blade, the rear end of said flange being integral with the front end of one of said lugs whereby said flange is reinforced by said lug, and a boss integral with the outer side of said other blade at the inner edge of the latter, said

boss and flange being disposed in co-operative relation with each other to provide jaws for tightening a bent wire connection of a hat frame.

6. A structure as specified in claim 1; together with a slight enlargement on the inner side of said other blade directly opposite said boss, said enlargement adding area to the boss-formed jaw and acting also as a spreader for the portions of the blades behind the pivots, to urge the cutting portions of said blades into effective cutting relation with each other.

In testimony whereof I have hereunto affixed my signature.

NELLIE OLIVE HENAUT.
